UNITED STATES PATENT OFFICE.

HENNING WENNERSTEN, OF CHICAGO, ILLINOIS.

BOTTLE-CAPPING DEVICE.

1,294,006.

Specification of Letters Patent. Patented Feb. 11, 1919.

Application filed June 10, 1918. Serial No. 239,139.

To all whom it may concern:

Be it known that I, HENNING WENNERSTEN, a citizen of the United States, residing at Chicago, in the county of Cook and State 5 of Illinois, have invented certain new and useful Improvements in Bottle-Capping Devices, of which the following is a description.

My invention belongs to that general class 10 of devices employed for applying the bottle caps or closures at present in extensive use, and has for its object the production of a simple, economical and effective device for the purpose described. To this end my invention consists in the novel construction, 15 arrangement and combination of parts herein shown and described and more particularly pointed out in the claim.

In the drawings, wherein like reference 20 characters indicate like or corresponding parts,

Figure 1 is a vertical central section of my improved device; and

Fig. 2 is a transverse section taken substantially on line 2—2 of Fig. 1.

In the drawings, 1 represents a suitable base of metal or other suitable material, provided with a pair of upright standards 2 rigidly secured to the base and extending 30 parallel to one another. Slidably mounted upon these standards is a transverse cross head 3 provided with extensions 4 through which the standards 2 pass as indicated. 5—5 are set screws extending through the 35 extensions 4 and adapted to contact with the standards 2 so as to adjust and set the cross head at any desired point, dependent upon the height of the bottle to be capped. The extensions 4 are each provided with 40 inwardly extending guides 6.

A follower or capping head 7 is provided

with forks 8 on each side adapted to loosely engage the guides 6. The lower face of the head is formed to receive the ordinary cap and retain the same in proper relative position to the bottle to be capped. A screw 9 is in screw threaded engagement with the cross head 3, and at its lower end rotatably engages the capping head 7, while at its upper end it is provided with a hand wheel 10, or equivalent construction, adapted to aid in conveniently turning the screw 9. Obviously the guiding parts on the cross head and the capping head may be modified as desired so long as they secure the proper seating of the capping head upon the bottle.

The mode of operation is apparent.

Having thus described my invention, what I claim as new and desire to secure by Letters Patent is:—

A bottle capping device comprising a suitable base provided with a pair of upwardly extending parallel standards, in combination with a coöperating cross head adjustably engaging the standards, said cross head being provided with means for locking the same in position upon the standards and with inwardly extending guiding means, a capping head positioned within the cross head with coöperating guiding means for engaging the cross head, and a screw in threaded engagement with the cross head with its lower end in operable engagement with the capping head, substantially as described.

In testimony whereof, I have hereunto signed my name in the presence of two subscribing witnesses.

HENNING WENNERSTEN.
